UNITED STATES PATENT OFFICE.

CHARLES A. BAILEY, OF CROMWELL, CONNECTICUT.

DESIGN FOR A TOY STOVE.

SPECIFICATION forming part of Design No. 26,326, dated November 24, 1896.

Application filed October 14, 1896. Serial No. 608,895. Term of patent 3¹ years.

To all whom it may concern:

Be it known that I, CHARLES A. BAILEY, a citizen of the United States, residing at Cromwell, in the county of Middlesex and State of Connecticut, have invented and produced a new and original Design for Toy Stoves, of which the following is a specification, reference being had to the accompanying drawings, illustrating the same, in which—

10 Figure 1 is a representation of an elevation of the front side of the stove. Fig. 2 is an elevation of the rear side of the same. Fig. 3 is a front elevation of the stove. Fig. 4 is a rear elevation thereof, and Fig. 5 is a plan 15 of the hearth.

This invention has relation to a certain new and original design for stoves; and it consists in the novel form and configuration of parts, all as hereinafter described, and illustrated 20 in the accompanying drawings.

Referring to the drawings, it will be observed that the general form of the body A, as viewed in side and elevation and in plan, is rectangular, with a depending curtain 25 flange B at the base and an overhanging top plate.

The rear portion C of the body, when viewed in plan, forms an even continuation of the body, but when viewed in side elevation is 30 seen to form an offset from the base, its bottom line or wall having an upward curve. At the opposite or front end of the body is a horizontal hearth projection D, having a generally flat surface with slightly-beveled lateral and front edges.

The "hot oven" E, arranged on the top of the body A, as shown, presents a general T shape or outline, having the upright portion E' and rectangular upper body portion E".

40 The curtain flange B extends entirely around the base and has a leg extension B' at each corner angle. This flange is ornamented upon its upper narrow band b by a raised vine and flower figure, the vine running alternately above and below the flowers. The 45 main body of the curtain flange B is ornamented on each side and end of the stove by a central ornamental shield or figure and a running vine with leaves and flowers, as 50 shown.

The front side of the stove above the cur-

tain flanges has the rectangular space or panel F below the small door G ornamented by the raised design shown. Above this panel is a raised bar f, and the fluted design f' above 55 said bar and below the small door. This door G is ornamented with a raised circular figure H, extended on the opposite sides, at H', giving it a somewhat oval form, the edge of this figure being scalloped and its center 60 ornamented with a figure representing a daisy. The four ends of the door have ornamental flower figures H". The large oven-door I has a raised central figure J similar to that on the small door, except its central ornamentation, which here consists of the scalloped figures J', the four ends of the door-panel having the flower figures I". The part C on this side of the stove is ornamented by the central figure K, surrounded at the four corners 65 of the panel by the ornamental figures K'.

The front of the heating box or oven E, on top of the body A, is ornamented on its lower upright portion E' by a central oval wreath e, within which the ornamental letters "J & 75 E S Co" are arranged as a monogram. To each side of this central figure are the ornamental scroll and flower figures e', as shown. The sliding doors E" of the upper part E' are 70 ornamented by the flower and running-vine 80 figures shown. The upper projection E" above the body of the heating-box is ornamented with the scroll and flower figures shown.

The rear side of the body A is ornamented 85 by a central design L, formed of a series of raised hexagonal blocks, and the panels or spaces M to each side of the same are ornamented by a central flower figure m, a shell-like figure m' to each side thereof, an inclosing 90 larger flower figure m", and at the upper and lower ends of the panels the smaller flower and leaf figures m". The rear surface of the extension C bears an ornamental design corresponding to that on the front face 95 of said extension. The back of the upper heating-box E is ornamented with the central vertical lines resembling a column, while to each side thereof is shown a vine figure bearing leaves and flowers.

At the front of the stove the hearth D has upon its upper surface the ornamental design 100

shown in Fig. 5, while the door N above the hearth bears a design similar to that on the small door G. The hinge end of each of the three doors G, I, and N are ornamented by the vertical pillar design shown.

The rear end of projection C is ornamented, in relief, by a central ring O, inclosing the scroll figures D, this central figure being immediately surrounded by the scroll figures Q, while the ends of the panel are filled by the

vine, leaf, and flower figures R, the ends of the panel being marked by the bars S.

What I claim is—

The design for a stove substantially as herein shown and described.

CHAS. A. BAILEY.
